J. H. VICKERS,

Latch.

No. 93,504.

Patented Aug 10, 1869.

United States Patent Office.

JOHN H. VICKERS, OF NORWICH, CONNECTICUT, ASSIGNOR TO NORWICH LOCK COMPANY.

Letters Patent No. 93,504, dated August 10, 1869.

IMPROVEMENT IN COMBINED KNOB-LATCH AND LOCK.

The Schedule referred to in these Letters Patent and making part of the same.

To all whom it may concern:

Be it known that I, JOHN H. VICKERS, of Norwich, in the county of New London, and State of Connecticut, have invented certain new and useful Improvements in Locks or Knob-Latches; and I do hereby declare that the following is a full and exact description thereof.

My improved lock may be used as a dead-lock for the night, (refusing to be opened from the outside, even by the proper key,) or it may be used as a night-latch, (being opened by the proper key from the outside,) or it may be used as an ordinary knob-latch, (being opened from either side by simply turning the knob.) These changes in the conditions may be induced by changing the position of a single piece, always accessible from the inside of the house.

My invention is more particularly designed for the street-doors of houses, but may be used on the doors of rooms in hotels, and in a great variety of situations.

I will first describe what I consider the best means of carrying out my invention, and will afterwards designate the points which I believe to be new.

The accompanying drawings form a part of this specification.

Figure 1 is a front view of the works of the lock when in a condition to be opened with the aid of the proper key;

Figure 2 is a corresponding view when in a condition to be opened by simply turning the knob; and

Figure 3 is a corresponding view when in a condition of a dead-bolt; that is to say, so that it cannot be opened by any means from the outside.

Figures 1^a 2^a and 3^a correspond to figs. 1, 2 and 3, respectively, and are views of the end of the lock, that end from which the bolt protrudes.

These figures are important, mainly, in showing the position of the visible part of the adjustable thumb-piece in the several conditions of the lock.

Similar letters of reference indicate like parts in all the figures.

Tints are employed merely to aid in distinguishing parts, and do not imply differences in material.

The material of the whole may be malleable-iron or brass.

A is the casing of the lock, which is screwed or otherwise secured to the door, the door having been recessed in the ordinary manner to receive it.

B is the bolt, widened at the back, and opened to receive the wings c c, of an ordinary turning-knob device C.

This bolt is impelled outward by a spring, D, arranged as represented.

All these parts are of the ordinary construction and arrangement.

E¹ E² are tumblers, made in the ordinary approved

manner, and adapted to serve, relatively, to a fence, b, which is carried on the bolt B.

The tumblers E¹ E² are pivoted on the hub C, which receives the shaft of the turning-knob, as before suggested.

I have not deemed it necessary to represent the shaft and the knobs. It may be readily understood that the shaft is an ordinary square shank, and that the knobs are mounted on each end, so that one is presented on the outer side of the door, and the other on the inner side of the door, and by applying the hand to either knob, and turning it, the hub C, and consequently the wings c c, are turned to act upon the bolt B.

G is a turning-post, mounted as represented, so that it is free to turn, unless prevented by the spring h, which stands in the open side of the cavity g.

This cavity g is rectangular in section, and extends the whole length of the turning-post G. It is adapted to receive the back or axis of a thin key.

A key-hole, i, in the front plate of the lock, indicated in red outline, is of a width corresponding to this recess or cavity g, and is of a length corresponding to the dimensions of the key. It allows the key to be introduced freely, and pressed home into such position that it can be turned.

In being pressed home, it forces back the spring h, and thus sets the parts free, so that it may be turned, carrying with it the turning-post G, and having its axis of motion coincident with the axis of the said post.

A stop, a, is provided, which arrests the motion of the key after it has made about five-eighths of a revolution.

In turning around, before it reaches the stop, its working-edge first acts upon and lifts the tumblers E¹ E², and afterwards acts against a suitable shoulder, B¹, on the bolt B, and forces back the bolt.

The key and the adjacent surfaces of the tumblers must be adapted to each other, so that, as the key turns, the tumblers will be lifted to exactly the right position, all of which will be readily understood by those familiar with tumbler locks.

J is a hollow turning-post, mounted in the position represented, and provided with a thumb-piece, which is presented on the inside of the door to allow it to be turned. It is made with an extension from the thumb-piece, reaching nearly through the centre of the turning-post J, and secured in position by a screw introduced from the other opposite end, but this construction is not material so long as the thumb-piece is secured to the turning post, so that it may operate it.

There are on the turning-post J two arms or wings, which are adapted to act on the tumblers. One wing, J¹, is adapted to the tumblers E¹, so that when this

arm J^1 is turned in the vertical position, it raises the tumblers $E^1 E^2$ to exactly the height required to allow the bolt to be drawn back.

By applying the thumb and finger to the thumb-piece, and adjusting the turning-post J , so that the wing J^1 is vertical, the tumblers $E^1 E^2$ are held in such position that they are of no effect.

In this condition the lock is an ordinary knob-latch, and may be operated from either side by turning either knob, and thus operate the wings $c c$.

The wing J^2 is nearly opposite to the wing J^1 , and is of such form, and so related to the tumblers $E^1 E^2$, that by turning the post J so as to lift the wing J^2 into contact with the tumblers, it lifts the tumblers into such position that they will not allow the fence b , and, consequently, the bolt B , to be moved. In this condition the lock is a dead-lock.

It cannot be operated by the wings $c c$, as an ordinary knob-latch, nor can it be operated by the key, because one of the tumblers is thrown into a position too high to allow the fence b to move. It will be readily understood that in this condition the key is powerless, because it cannot reach the tumbler which is so elevated. But by turning the post J into an intermediate position, so that neither of the wings J^1 nor J^2 are elevated, the tumblers $E^1 E^2$ are both liberated, and are allowed to drop by gravity or by the force of the springs e , arranged in the ordinary manner, and in this

condition the lock can be operated by the key, but it cannot be operated without the key, because the tumblers, by assuming too low a position, will prevent it serving as an ordinary knob-latch.

A spring, K , mounted as represented, presses against the lower side of the turning-post J , and is adapted thereto, so that it holds the turning-post in either of the three positions in which it may be adjusted.

I employ false notches on the tumblers and on the fence, or can dispense with them, as may be desired.

My lock may be modified in many of the details without interfering with its performance in the three ways herein described.

I propose, in some instances, to employ a large number of tumblers; in others, a single tumbler may be adequate for all the strength and safety which may be considered necessary.

Having now fully described my invention,

What I claim as new therein, and desire to secure by Letters Patent, is as follows:

Pivoting the tumblers of a tumbler-lock upon the hub C of a knob-latch, mechanism combined therewith to facilitate the manufacture and the compactness of the combined-mechanism, as herein set forth.

JOHN H. VICKERS.

Witnesses:

A. F. SMITH,

P. ST. M. ANDREWS.
